UNITED STATES PATENT OFFICE.

ELMER E. LANE, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SKIVING-MACHINE.

1,260,551.

Specification of Letters Patent. Patented Mar. 26, 1918.

Application filed October 10, 1914. Serial No. 866,064.

To all whom it may concern:

Be it known that I, ELMER E. LANE, a citizen of the United States, residing at Beverly, in the county of Essex and State 5 of Massachusetts, have invented certain new and useful Improvements in Skiving-Machines; and I do hereby declare the following to be a full, clear, and exact description of the invention, such as will enable others 10 skilled in the art to which it appertains to make and use the same.

The present invention relates to skiving machines and more particularly to blank feeding mechanism for machines for skiving box toes and counters for boots and 15 shoes.

In a well known form of skiving machine of the type illustrated in U. S. Letters Patent to Jacob R. Scott, 760,082, dated 20 May 17, 1904, a pile or series of blanks is supported in a race-way or magazine from the bottom of which one blank at a time is fed to the pressure and die rolls and to the skiving mechanism by devices which 25 are constructed and arranged to be automatically disconnected from their actuating mechanism when the pile of blanks in the magazine is reduced to a predetermined minimum, so that the feeding of blanks will 30 cease while the other portions of the machine continue in operation. In this type of machine, however, the feeding devices are often given a shortened feeding stroke or movement before being brought to their 35 final position of rest, and in such shortened stroke are liable to advance a blank to the die roll and pressure devices, but out of proper time relation to the movement of the die roll, thereby causing a mutilation of the 40 blank or stoppage of the machine or damage to or breakage of some of its parts.

The primary object of the present invention is to avoid this objection by so constructing the feeding devices and their actuating mechanism that when the pile of blanks reaches a predetermined minimum and the feeding devices and their actuating mechanism are disconnected, there will be 45 no liability of a shortened feeding movement or stroke.

With this and other objects in view, apparent to those skilled in the art from the accompanying specification, the present invention consists of the devices and combina-

tions of devices hereinafter described and 55 more particularly defined in the claims.

In the accompanying drawings which illustrate a preferred form of the present invention; Figure 1 is a side elevation of a leather skiving machine of the general type 60 disclosed in Letters Patent to Jacob R. Scott, No. 969,987 and embodying the present invention; Fig. 2 is an enlarged section of the middle portion of the machine; Figs. 3 and 4 are enlarged details in side and rear 65 elevation respectively, of portions of the tripping lever with its connections; Fig. 5 is a top plan view of the same; Fig. 6 is a vertical section on line 6—6, Fig. 5; Fig. 7 is a side elevation, and Fig. 8 is a trans- 70 verse section on line 8—8, Fig. 7, of the crank and connections for actuating the trip lever.

In the machine illustrated in the drawings, the blanks to be skived are arranged 75 in a vertical pile in the hopper or magazine 1, the lowermost blank being pressed down by a follower 74 secured to the lower end of the vertically movable rod 2 having the weighted upper end 3 which carries the ad- 80 justable abutment screw 4. The rod 2 is provided with the rack 5 for raising and lowering the follower by power, as is well known in this type of machine. The blanks are fed through the passage or opening 8 85 to the die roll 9 and pressure devices 10 mounted respectively upon the shafts 11 and 12 driven by suitable gearing from the main driving shaft 13. The die roll is provided with the customary blank positioning die 90 cavity 14 and the skiving knife 15 is supported rigidly upon the frame of the machine directly behind the bight of the die roll and pressure devices. One blank after another from the bottom of the pile of 95 blanks in the magazine is fed to the die roll at the predetermined time with relation to the position of the die cavity by means of the feeding fingers 18 secured to the front of the feed slide 19 which is provided with 100 the depending ears 20 in which is mounted the transverse driving pin 21.

The feed slide is actuated to make its feeding and its return stroke from an oscillating shaft 23 mounted in the frame of the 105 machine, and driven by suitable connections from the main shaft. Fixed upon the oscillating shaft 23 is the lever 24, to the up-

per end of which is pivotally connected the link 25 provided at its free end with the upstanding shoulder or abutment 26 and recess or notch 27. The free end of the link 5 is arranged to be raised or lowered to render the feed slide actuating mechanism operative or inoperative, by means of the lever 30 pivoted at one end on the frame of the machine and carrying at the other 10 end a cam roll 31 located in a cam path 32 formed in the lower portion of the link. When the link is in its raised or operative position, the pin 21 on the feed slide will be engaged in the notch 27 in the link and 15 the slide will be given alternate feeding and return movements. When this link is lowered the notch is withdrawn from the pin 21 so that the link is inoperative to impart to the feed slide a return movement. The 20 shoulder 26 is of sufficient height, however, to engage the pin 21 even when the link is in its lowermost or inoperative position, so that the feed slide will always be brought to the end of its feeding movement as its 25 final position of rest.

The lever 30 and link 25 are raised and lowered by suitable mechanism, including a treadle 35 pivoted upon the frame of the machine, a pivoted lever 36 and connections 30 37 and 38, the treadle being depressed by the operator to raise the link into operative position, and the reverse movements taking place under the action of the spring 39. The treadle is held in depressed position by 35 means of a latch lever 40 which may be actuated against the tension of spring 41 by the foot of the operator if for any reason during the regular operation of the machine it is desired to bring the feed slide to rest. 40 In practice the operator is careful to trip the latch lever 40 only during a feed movement of the feed slide so that the latter will complete that feeding stroke and then come to rest, thus avoiding all possibility of a 45 shortened feeding stroke and of mutilation of a blank or damage to the machine.

In machines of the type above referred to means are provided for automatically rendering the feed slide actuating mechanism 50 inoperative when the pile of blanks in the hopper is reduced to a predetermined minimum, and these means comprise briefly a lever pivoted upon a fixed support, one end of the lever extending into the path of 55 movement of the abutment screw 4 to be engaged by said screw when the supply of blanks is nearly exhausted and the other end of the lever being connected to the latch lever 40 to actuate the latter and permit 60 the spring 39 to throw the link 25 into its lowermost or inoperative position.

It will be observed that the point in the operation of such machine when the link 25 is dropped to its lowermost or inoperative 65 position bears no fixed or predeter-

mined time relation to the movement of the feed slide, but depends wholly upon the movement of the follower which rests upon the pile of blanks. Consequently, the lowering of the link may occur during either 70 the feeding or the return movement of the feed slide. In the former event the shoulder 26 will continue to actuate the feed slide until it reaches its innermost position, where it comes to its permanent position of rest. 75 In the latter event, however, the feed slide and its actuating mechanism will be immediately disconnected and the feed slide will stop wherever it may happen to be, but on the next feeding stroke of the link 25 the 80 shoulder 26 will again engage the pin 21 and the feed slide will return to its innermost position where it comes permanently to rest.

It sometimes happens during this shortened feeding movement that the blank at the bottom of the pile is carried by frictional engagement with the feeding fingers through the passageway 8 and into engagement with the die roll and pressure devices. 85 A blank so fed, however, will not be presented to the die roll in proper relation to the die cavity and as a result the blank will be mutilated and the machine may be stopped or some of its parts damaged or 90 broken.

This objection is avoided in the present invention by providing means for automatically actuating the latch lever 40 in predetermined time relation to the movements 100 of the feed slide so that the link 25 will never be lowered during the return or idle stroke of the feed slide and the latter cannot make a shortened feeding stroke immediately prior to its coming to its permanent 105 position of rest.

In the machine illustrated in the drawings, these results are accomplished in the following manner:

Rotatively mounted in a boss or projection 45 at the top of the frame of the machine is the stud or shaft 46, one end of which 47 is eccentric (see Fig. 6). Pivoted upon this eccentric portion 47 is the lever 48, one end of which 49 extends into the 115 path of movement of the abutment screw 4, while the other end 50 is connected by means of the rod 51 to the latch lever 40.

The stud 46 is oscillated from the oscillating shaft 23 by means of the member 54 rigidly secured upon the opposite end of said shaft from the eccentric 47, and carrying the forked arm 55, the shank of which 56 extends through a portion of the member 54 and is secured by the nut 57. Pivotally connected to the arm 55 is the rod 58, to the lower end of which is attached the member 59 provided at its lower portion with a bearing for the sleeve 60 mounted upon the shank of the bearing screw 61, a washer 62 130

and nut 63 holding the member 59 upon the bushing. Secured to the end of the oscillating shaft 23 by means of the screw 65 and pins 66 is the crank arm 67 provided with 5 the guideway 68 to receive the square head 69 of bearing screw 61.

It will be noted that the nut 63 not only holds the washer 62 firmly against the bushing 60, but also serves to clamp the bearing 10 screw 61 in the desired adjustment upon the crank arm 67.

The above described construction is such that the stud 46 is oscillated from the shaft 23 in predetermined timed relation to said 15 shaft, and the eccentric 47 is so arranged that it will raise the lever 48 while the feed slide is making its feeding stroke, the end 50 of this lever being restrained by the rod 51 and spring 41. The relative lengths of the 20 two arms of the lever 48 are such that the throw of the eccentric is multiplied a number of times at the free end 49 of the lever, which is thus given at each cycle of operation 25 of the machine a vertical movement of considerable extent, very much greater than the downward movement of the follower or abutment screw during the same period. So long as the abutment screw 4 has not descended far enough to be engaged by the upwardly moving end 49 of the lever 48, the machine will continue to operate regularly, but when the pile of blanks in the hopper are reduced to the predetermined minimum, the screw 4 will be in position to be engaged 35 by the arm 49 on its upward movement and when so engaged will stop the free end of the lever and further movement of the eccentric will actuate the other arm 50 against the tension of spring 41 and through the rod 40 51 will trip the latch 40 and permit the spring 39 to raise the treadle and depress the link. Since this must occur, if it occurs at all, during the feeding stroke of the feed slide, the link will continue to actuate the 45 feed slide until the latter reaches its innermost position, where it will remain at rest while its actuating mechanism continues to operate.

Owing to the fact that the movement of 50 the free end 49 of the lever 48 is of relatively large extent compared with the movement of the abutment screw 40 during a cycle of operation of the machine, the latch 40 will be actuated at substantially the same 55 point in such cycle of operation and the link lowered at substantially the same position of the feed slide.

The operation of the above described machine is as follows:—A pile of blanks having been inserted in the magazine with the follower properly adjusted and in engagement with the topmost blank and the link 25 in its lowered or inoperative position, the main shaft 13 is set in operation, thereby 60 causing the shaft 23 to oscillate. This shaft

in turn imparts feeding movements to the link 25, but without actuating the feed slide. Through the crank arm 67 oscillations are imparted to the eccentric 47 resulting in regular upward and downward movement 70 of the end 49 of lever 50.

When the operator desires to set the feeding mechanism in operation, he depresses the treadle 35, thus raising the link 25, and holds the treadle down and the link raised 75 until the link reaches the limit of its inward movement, when the notch 27 will engage the pin 21, the downward movement of the treadle 35 at this time permitting the latch 40 to become operative to hold the treadle 80 in its lowest and the link in its highest position. Thereafter the movements of the link 25 will be imparted to the feed slide and the latter will feed the blanks successively through the passageway 8 to the die roll and 85 pressure devices, and thence to the skiving knife.

As the blanks are fed from the bottom of the pile or series, the height of the pile diminishes and the follower descends until its abutment 90 screw reaches a position where it will be engaged by the free end 49 of lever 48 while the latter is making its upward movement due to the oscillation of the eccentric 47. The continued movement of the eccentric 95 raises the opposite end 50 of the lever and actuates the latch 40 to release the treadle, whereupon the spring 39 immediately raises the treadle and depresses the link 25. The parts are so adjusted that this occurs during 100 the feeding stroke of the feed slide, and preferably at or near the end of its feeding movement. If the link is lowered before the feeding movement is completed, the feed slide will nevertheless continue to be advanced by the link until the limit of its inward movement is reached, where it will come to and remain at rest.

The follower may now be raised and a new supply of blanks placed in the magazine 110 and the feeding mechanism again set in operation as above described.

While the illustrated embodiment of the invention is shown as a feeding device for skiving machines, the feeding device is not, 115 however, limited to use in a skiving machine but may be employed in any machine in which blanks are intermittently presented in timed relation to the operation of the blank treating mechanism and in which the feeding device is started and stopped while the mechanism continues to operate.

Having thus described and explained the nature and principle of the present invention, and what is now considered the preferred form of said invention, I claim:

1. Blank feeding mechanism for skiving machines comprising, means for supporting a series of blanks, means for feeding a blank, actuating mechanism for said means, and

devices controlled by the series of blanks for rendering said feeding means inoperative at a predetermined point only in their cycle of operation.

5. 2. Blank feeding mechanism for skiving machines comprising, means for supporting a series of blanks, means for feeding a blank from the series, actuating mechanism for said means, and devices operating automatically at a predetermined point in the cycle of operation of the machine for rendering the feeding means inoperative.

15. 3. Blank feeding mechanism for skiving machines comprising, means for supporting a series of blanks, a feed slide for feeding a blank from the series, actuating mechanism for the feed slide, means for automatically disconnecting the feed slide and its actuating mechanism, and devices operating 20 to prevent the automatic disconnection of said means during the return or idle stroke of the feed slide.

25. 4. Blank feeding mechanism for skiving machines comprising, a feed slide for feeding a blank, actuating mechanism for the feed slide, and means for disconnecting the feed slide and its actuating mechanism only after a full feeding movement of the feed slide.

30. 5. Blank feeding mechanism for skiving machines comprising, means for supporting a series of blanks, a feed slide for feeding a blank from the series, actuating mechanism for the feed slide, means for disconnecting the feed slide and its actuating mechanism, automatic devices for rendering said means operative at a predetermined point only in the cycle of operation of the machine, and devices under the control of the operator for 40 rendering said means operative at other than the predetermined point in the cycle of operation of the machine.

45. 6. Blank feeding mechanism for skiving machines comprising, means for supporting a series of blanks, a feed slide for feeding a blank from the series, actuating devices for the feed slide, and means controlled by the series of blanks for disconnecting the feed slide and its actuating mechanism only when 50 the feed slide is at the end of its feeding movement.

55. 7. Blank feeding mechanism for skiving machines comprising, a magazine for supporting a pile of blanks, a follower engaging the topmost blank of the pile, a feed slide for feeding the lowermost blank of the pile, actuating devices for the feed slide, and connections between the follower and said devices operating automatically when the 60 follower reaches a predetermined point to disconnect the feed slide and actuating devices at a predetermined position of the feed slide.

65. 8. Blank feeding mechanism for skiving machines comprising, a magazine for sup-

porting a pile of blanks, a follower engaging the topmost blank of the pile, a feed slide for feeding the lowermost blank of the pile, actuating mechanism for the feed slide, means for disconnecting the feed slide and its actuating devices, a member moving in timed relation to said actuating mechanism for rendering the disconnecting means operative, devices for moving said member, and means connected with the follower and arranged to come into position to be engaged by said member.

9. Blank feeding mechanism for skiving machines comprising, a magazine for supporting a pile of blanks, a follower engaging the topmost blank of the pile, a feed slide for feeding the lowermost blank of the pile, actuating devices for the feed slide, means for disconnecting the feed slide and its actuating devices, a lever connected at one end to 80 said means, a pivotal support for the lever midway its ends, means for moving the support in timed relation to the actuating devices for the feed slide, and an abutment connected with the follower and arranged to 90 come into position to be engaged by the free end of the lever during the movement of the pivotal support.

10. Blank feeding mechanism for skiving machines comprising, a magazine for supporting a pile of blanks, a follower engaging the topmost blank of the pile, an abutment carried by the follower, a feed slide for feeding the lowermost blank of the pile, a shaft and connections for actuating the feed slide, 100 means for disconnecting the shaft and feed slide, a lever, an eccentric upon which the lever is pivoted, one end of the lever being connected to said means for disconnecting the shaft and feed slide and the other end 105 extending into the path of movement of the abutment carried by the follower, and connections between the shaft and eccentric for actuating the eccentric in timed relation to the feed slide.

11. Blank feeding mechanism for skiving machines comprising, a magazine for supporting a pile of blanks, a feed slide for feeding the lowermost blank of the pile, means for actuating the feed slide, devices 115 including a latch under the control of the operator for rendering said means inoperative, and automatic mechanism controlled by the pile of blanks in the magazine and operating at a predetermined point in the cycle 120 of operation of the machine for actuating the latch.

12. Blank feeding mechanism for skiving machines comprising, a magazine for supporting a stack of blanks, a slide for feeding the blanks one at a time, actuating mechanism for the feed slide, means for connecting the slide with its actuating mechanism, devices controlled by the movement of the stack of blanks for disconnecting the feed 125 slide.

13. Blank feeding mechanism for skiving machines comprising, a magazine for sup-

slide and its actuating mechanism, means for setting said devices for operation when the stack is reduced to a predetermined point, and means to limit the operation of said devices to a predetermined period in the cycle of operation of the machine after the stack has been reduced to said predetermined point.

13. Blank feeding mechanism for skiving machines comprising, blank feeding means, means for operating the feeding means, devices for stopping the feeding means while the machine continues to operate, and means to limit the operation of said stopping mechanism to a period when the feeding means has reached the end of its feeding movement.

14. Blank feeding mechanism for skiving machines comprising, a blank positioning device, means for feeding blanks to said device, means for actuating the feeding means, means for connecting the feeding means with its actuating means, means for moving the positioning device in timed relation to the feeding means, means for operating the connecting means for disconnection of the

feeding means and its actuating mechanism, and means to insure that the connection of the feeding means with its actuating mechanism during the continued operation of the machine will operate to advance the next blank in timed relation to the movement of the blank positioning device.

15. A blank feeding device for supplying blanks to the skiving mechanism of a skiving machine comprising, a blank positioning device, a feeding member, means for actuating said member, devices for connecting and disconnecting said member and its actuating mechanism while the skiving mechanism continues to operate, and means to insure that the connection of said member with its actuating mechanism for feeding blanks will be in a position to present the next succeeding blanks in timed relation to the movement of the blank positioning device.

It is hereby certified that in Letters Patent No. 1,260,551, granted March 26, 1918, upon the application of Elmer E. Lane, of Beverly, Massachusetts, for an improvement in "Skiving-Machines," an error appears in the printed specification requiring correction as follows: Page 5, lines 14-15, claim 13, for the word "mechanism" read *devices*; and that the said Letters Patent should be read with this correction therein that the same may conform to the record of the case in the Patent Office.

Signed and sealed this 7th day of May, A. D., 1918.
